The ornamental design for a clamp for supporting a suction cup, as shown and described.

DESCRIPTION

FIG. 1 is a perspective view of a clamp for supporting a suction cup in accordance with my new design;

FIG. 2 is a top plan view thereof;

FIG. 3 is a bottom view thereof;

FIG. 4 is a front view thereof;

FIG. 5 is a back view thereof;

FIG. 6 is a right view thereof; and,

FIG. 7 is a left view thereof.

The broken lines in the drawings and the areas within them depict portions of the clamp for supporting a suction cup that form no part of the claimed design.
